Int. Cl. D9—03

U.S. Cl. D9—193

FIG. 1 is a front perspective view of a doll package showing my new design;

FIG. 2 is a front elevational view; and

FIG. 3 is a rear elevational view thereof.

The characteristic feature of my design is the package having a stiff cardboard or the like member at the upper side thereof, an opaque backing sheet, a transparent flexible covering film across the front of the package and a naked female doll figure surrounded by furry hair positioned between the transparent cover sheet and the opaque backing sheet.

I claim:

The ornamental design for a doll package, substantially as shown and described.
